Dec. 1133

Garrison Smith & Henry Brown of Philadelphia, Pa.

Assignors to

Cox, Whitman & Cox, of same place.
Letters Patent No. 1133. - Dated Aug. 16, 1859.

The schedule referred to in these Letters Patent and making part of the same.

To all whom it may concern:

Be it Known, That we Garrison Smith & Henry Brown of Philadelphia, in the County of Philadelphia and State of Pennsylvania, have invented a new and Original Stove Design and we do hereby declare that the following is a full clear and exact description of the same, reference being had to the annexed drawings forming part of this specification;

The ornaments in bas-relief upon the castings A, B, C and D, constitute the subject of this patent.

The door frame A, is of form shown in the drawing bearing the sweeps and scrolls a and b as set forth.

The portion B, constituting the top of the stove is fluted on its under surface as seen at c, and has the over hanging wavy edge d, within which are the figures e, in bas-relief.

The plate C, which is the ash pit cover, has upon each corner a foliage ornament f, enclosed in a rim made up of projections g. Upon the edge of the plate are the figures h, in bas-relief.

The base plate D, has a curved upper surface and a sweeping edge ornamented with scrolls m, and n, and foliage p, and q.

The design configuration and arrangement of the several ornaments are as set forth in the drawing.

We Claim the design configuration and arrangement of the ornaments on the plates as described forming a new stove design.

In testimony whereof we have hereunto signed our names before two Subscribing Witnesses,

G. M. P.

Wm. J. S.

D. Brazier.

Charles Schmitz.

Garrison Smith;
Henry Brown.
